UNITED STATES PATENT OFFICE

FREDERICK R. ERBACH, OF DETROIT, MICHIGAN, ASSIGNEE TO KELVINATOR CORPORATION, OF DETROIT, MICHIGAN, A CORPORATION OF MICHIGAN

REFRIGERATION

Application filed January 22, 1927. Serial No. 162,699.

My invention relates to mechanical refrigeration, and particularly to means for pre-cooling milk prior to its storage in a refrigerator cabinet, and the principal object 5 of my invention is to provide new and improved means of this type. In the drawings accompanying this specification and forming a part of this application I have shown, for purposes of illustration, one form which my 10 invention may assume. In these drawings:

Figure 1 is a front elevation of a mechanical refrigerator in which this embodiment of my invention is included.

Figure 2 is a side elevation of the same.

Figure 3 is a longitudinal vertical section 15 through this embodiment of my invention, while

Figure 4 is a transverse vertical section of the same.

20 The embodiment of my invention disclosed herein comprises a refrigerator cabinet 11 having a compartment 12 for housing the compressor unit of the system, and a compartment 13 for storage of the articles to be 25 refrigerated, in this instance cans of milk.

Means for pre-cooling the milk is disposed exteriorly of the refrigerator cabinet 11 and comprises a pair of spaced end plates 14 and 15 supported by the brine pipes 16 and 17 30 which in turn are supported by the studs 18 and 19 projecting from a wall of the refrigerator. The end plates 14 and 15 are provided with a plurality of recesses 20 to accommodate the ends of a plurality of pipes 35 21 arranged in parallel relation and having their ends so connected that a continuous zig-zag passage is formed between the inlet pipe 16 and the outlet pipe 17 through which a refrigerant is circulated by thermosiphonic 40 action, or by a pump, not shown.

This assembly of end plates 14 and 15 pipes 21 is enclosed by an open top casing 22 which contains brine, or like heat conducting fluid, which is cooled by the refrigerant flowing 45 through the pipes 21. The ends of the casing 22 have outwardly extending enlarged portions 23 forming means to guide the flow of milk which is being cooled. The casing 22 is detachably held in assembled relation with 50 respect to the pipes 21 by means of rings 24

and 25 carried by the pipes 16 and 17 respectively, and engaging studs 31 and 32 on the ends of the casing.

A discharge trough 26, having in its bottom a plurality of perforations 27, is supported by the brackets 14 and 15 above the pipes 21 and casing 22, and serves as a receiver for the milk which is to be cooled, and carries, disposed therebelow, an upwardly curved plate 28 which has the dual function of closing the 55 open end of the casing 22 and of guiding the outflowing milk onto the outer surface thereof.

A receiving trough 29, having a discharge spout 30 is disposed below the casing 22 and 60 detachably connected thereto by means of rings 33 carried by the trough 29 and lugs 34 carried by the end walls of the casing 22 and serves as a receiver for the cooled milk which passes through the spout 30 into the receiving can 35 supported by the shelf 36 spaced 70 a suitable distance below the trough 29.

From the above description it will be obvious to those skilled in the art that I have provided an improved milk cooler for use in 75 a mechanical refrigerator.

At the same time it will also be obvious to those skilled in the art that the particular embodiment of my invention herein shown and described may be variously changed and 80 modified without departing from the spirit of my invention or sacrificing the advantages thereof, and it will therefore be understood that the disclosure herein is illustrative only, and that my invention is not limited thereto. 85

I claim:

1. In a liquid aerating and cooling apparatus, a structure including end plates having tubular recesses and pipes engaging the recesses to form therewith a continuous passage for the flow of heat absorbing fluid therethrough, a housing surrounding said structure, said housing being adapted to contain a heat absorbing fluid, means for discharging liquid over the exterior surfaces of 90 said housing, means for receiving the liquid flowing from said housing, and means for detachably associating said housing and said receiving means with said pipes.

2. In a liquid treating apparatus, a struc- 100

ture including end plates having substantially semi-circular tubular recesses therein and parallel pipes engaging the recesses in said end plates and forming therewith a continuous passage for the flow of heat absorbing fluid, an open topped housing surrounding said structure adapted to contain brine, means for discharging liquid to be treated over the exterior surface of said housing, means for receiving the liquid flowing from said housing, and means for detachably associating said housing and said receiving means with said structure.

3. In a liquid treating apparatus, a structure including end plates having tubular recesses therein and pipes engaging the recesses to form therewith a sinuous passage for the flow of refrigerant fluid, an open topped housing surrounding said structure, said housing having outwardly extending ends to direct liquid to be treated against the exterior surface, means for discharging liquid over the top of said housing, means for receiving the liquid flowing by gravity from the bottom of said housing, and means for detachably connecting said housing and said receiving means to structure.

4. In a liquid treating apparatus, a structure including end plates provided with recesses therein and pipes engaging the recesses forming therewith a sinuous passage for fluids, an open topped housing surrounding said structure, said housing being adapted to contain a heat absorbing fluid and having corrugated walls to increase the heat transfer area thereof, a cover plate for the top of said housing, a trough for discharging liquid to be treated upon said cover plate, means for receiving the liquid flowing from said housing, and means for detachably connecting said housing and said receiving means to said structure.

5. In a liquid treating apparatus, a structure including end plates provided with recesses and parallel pipes cooperating with the recesses to form a passage for the flow of heat absorbing fluid therethrough, a housing surrounding said structure, said housing being adapted to contain a heat absorbing fluid and having corrugated walls to increase the heat transfer area thereof, a curved cover plate for the top of said housing adapted to direct liquid to be treated against the upper exterior corrugated walls, means for discharging liquid to be treated on said cover plate, means for receiving the liquid flowing from said housing, lugs secured to the upper and lower end portions of said housing, means for connecting said receiving means to said lower lugs, and means for connecting said upper lugs to said structure.

6. In a liquid treating apparatus, a structure including end plates provided with recesses therein and pipes associated with the recesses to form a sinuous passage for the

flow of heat absorbing fluid, a housing surrounding said structure, a trough for discharging liquid to be treated over the top of said housing, a top cover plate for said housing, adapted to direct the liquid against the exterior walls of said housing, a trough for receiving said liquid draining from said housing, and means for connecting said housing and said receiving trough to said structure.

7. In a liquid treating apparatus, a structure comprising end plates provided with recesses, inflow and outflow pipes connecting with apertures in said end plates, and pipes cooperating with the recesses in said end plates to form a passage for the flow of heat absorbing fluid therethrough; a brine containing housing surrounding said structure; means for discharging liquid to be treated over the exterior of said housing; a trough for receiving the liquid draining from said housing; means for connecting said housing to said inflow and outflow pipes; and means for connecting said trough to said housing.

8. In a liquid treating apparatus, a structure comprising end plates provided with recesses therein, pipes cooperating with the recesses to form a passage for the flow of heat absorbing fluid therethrough; a brine containing housing surrounding said pipes; a cover plate for the top of said housing; a trough placed over said cover plate, said trough having apertures in the bottom wall thereof for discharging liquid to be treated on said cover plate; a trough disposed below said housing for receiving the liquid flowing over said housing; and means for detachably connecting said housing and said receiving trough to said structure.

9. In a liquid treating apparatus, a structure comprising end plates provided with recesses, an inflow pipe engaging an aperture in one of said end plates, an outflow pipe engaging an aperture in the other of said end plates, and pipes connecting the recesses in said end plates; a housing surrounding said structure; means for discharging a liquid to be treated over said housing; means for receiving the liquid discharged over said housing; lugs secured adjacent the upper and lower edges of the housing; and means for detachably connecting said housing to said inflow and outflow pipes; and means for connecting said receiving means to said housing.

10. In a liquid treating apparatus, a structure comprising end plates provided with recesses and an aperture, an inflow pipe engaging the aperture in one of said end plates, an outflow pipe engaging the aperture in the other of said end plates, and pipes cooperating with the recesses in said end plates to form a sinuous passage for the flow of refrigerant therethrough; a housing thermally associated with and surrounding said structure; a cover plate for the top of said hous-

ing; a trough for discharging liquid to be treated on said cover plate; a trough for receiving the liquid discharged from said housing; lugs secured to the ends of said housing; 6 rings for detachably connecting said lugs to said inflow and said outflow pipes; and means for connecting said receiving trough to said housing.

In testimony whereof I hereunto affix my
10 signature.

FREDERICK R. ERBACH.
